(57) CLAIM

The ornamental design for a two tier organizer, as shown and described.

DESCRIPTION

FIG. 1 is a top perspective view of a two tier organizer, showing my new design;

FIG. 2 is a bottom perspective view thereof;

FIG. 3 is a front elevational view thereof;

FIG. 4 is a rear elevational view thereof;

FIG. 5 is a left side view thereof;

FIG. 6 is a right side view thereof; and,

FIG. 7 is a top plan view thereof.

The broken lines in the figures are for the purposes of illustrating portions of the two tier organizer, which form no part of the claimed design.
